WELL PACKER

Herman L. Sandlin and Adelbert Barry, both of Houston, Tex., assignors, by mesne assignments, to Jersey Production Research Company, Tulsa, Okla., a corporation of Delaware

Filed Sept. 25, 1961, Ser. No. 141,942
2 Claims. (Cl. 166—187)

This invention relates generally to inflatable or expandable balloon-type packers and is a continuation-in-part application of application Ser. No. 699,725, entitled "Well Packer," filed November 29, 1957, by Herman L. Sandlin and Adelbert Barry.

More particularly, the invention relates to an inflatable sleeve type well packer made in separate layers, at least one of which is formed of material having different inflate and hardness properties than the others.

One present sleeve type well packer design utilizes an inflatable rubber bladder provided with metallic reinforcing means and attached to metallic end support members. In the fabrication of this packer, a single piece natural rubber bladder is applied in a transfer moulding operation, which forms a solid mold rubber inflatable element bonded to the reinforcing means and to the end support members. If the bladder is damaged when in use or if the bladder is defectively formed in the molding process, it is difficult to salvage the end support members and the metallic reinforcing means. The only known ways to salvage these metal parts are to dissolve the rubber by undesirable, time-consuming chemical means or to burn off the rubber with resultant damage to the metallic members. Because of the superior strength and elasticity of natural rubber at well temperatures as compared to synthetic compounds, it is preferred to make the bladder of this material.

In one known arrangement of this type packer, its expandable sleeve or bladder is expanded from the inside with fresh water harmless to the bladder and carried initially within a positive displacement pump which is made part of the well pipe string. Although inflating water does not adversely affect the inner rubber of the single-piece packers, the borehole wall may abrade and borehole fluids in many cases attack and damage or destroy the outer cover rubber.

A primary object of the present invention is to provide an inflatable sleeve packer in which the outer surface thereof is resistant to the destructive effect of well fluids and abrasion, and in addition has a desirably large ratio of collapsed to expanded packer diameter. It is a further object of the present invention to provide an inflatable type packer in which the metal parts are easily salvaged. A further object of the invention is to provide an inflatable packer in which the inflatable element or elements are readily replaceable.

Briefly, the invention essentially comprises a well packer formed of separate layers which include an inflatable inner sleeve; an expandable filler sleeve surrounding the inner sleeve; an expandable outer sleeve surrounding the filler sleeve; and a reinforcing sleeve arranged between the filler and outer sleeves; the inner sleeve material is of greater elasticity and of lesser durometer hardness than the material forming the outer sleeve. Also, if desired, the filler sleeve may be formed of material having the hardness of the outer sleeve but greater elasticity.

The above object and other objects and advantages of the invention will be apparent from a more detailed description of the invention taken in conjunction with the drawings wherein:

FIG. 1 is a vertical, sectional view of the assembled packer of the invention;

FIG. 2 is a view taken on lines 2—2 of FIG. 1; and

2

FIG. 3 is a perspective cutaway view of the inner inflatable packer element.

For a more complete description of the invention, reference is made to the drawings in greater detail. In FIG. 1 is shown a hollow mandrel 10 formed to provide passageways 11 and 12 and a central bore 9 therein and adapted to be connected at the upper end to a packer pump or other packer inflating means (not shown), and at the lower end to a tail pipe or other tubing string (not shown). Upper and lower support members 13 and 14, respectively, are slidably arranged on mandrel 10. An inner inflatable sleeve bladder 15 surrounds mandrel 10 and is arranged between upper and lower support members 13 and 14, respectively. Bladder 15 is formed to provide upper and lower recesses 16 and 17 adjacent the upper and lower ends, respectively, of bladder 15, which in turn provide lip portions 18 and 19 on bladder 15.

An expandable sleeve assembly generally designated 20 surrounds bladder 15 and comprises upper and lower end plates 21 and 22 formed to provide circumferential recesses 23 and 24, respectively, therein; a reinforcing sleeve 25 formed for example of braided ribbons or wire arranged in recesses 23 and 24 and secured therein by means of a resin in accordance with the disclosure in U.S. patent application Serial No. 660,210, entitled "Anchoring Reinforcing Cables or Braids in Well Packers," by Herman L. Sandlin, filed May 20, 1957; an expandable rubber filler sleeve 26 arranged between sleeve 25 and inner bladder 15; and an outer expandable sleeve 27 arranged about sleeve 25. Upper end plate 21 is threaded to support member 13 as at 30, and lower end plate 22 is threadedly secured to lower support member 14 as at 31.

The packer is preferably employed in conjunction with hydraulic load adjusters such as disclosed and claimed in U.S. Patent No. 2,779,419, entitled "Improvement in Cable Reinforced Inflatable Packer," by W. D. Mounce.

The hydraulic arrangement as shown in FIG. 1 includes an upper stationary member 32 threaded to mandrel 10 as at 33, and a lower stationary support member 34 threaded to mandrel 10 as at 35. A head 36 is threadedly connected to support member 13 as at 37. Head 36, support member 13, stationary member 32, and mandrel 10 cooperate to form a reservoir or fluid chamber 40; and stationary member 34, lower support member 14 and mandrel 10 cooperate to provide a reservoir or fluid chamber 41. Fluid chambers 40 and 41 fluidly communicate via passageway 12 in mandrel 10. Various sealing means are provided for the upper portion of the packer apparatus. Thus, sealing means 50 and 51 are arranged on head 36 and are adapted to seal off the spaces between support member 13 and head 36, and between head 36 and mandrel 10, respectively. Sealing means 52 are arranged on upper stationary member 32 and are adapted to seal off the space between support member 13 and stationary member 32. Also, sealing means 53 are arranged on support member 13 and are adapted to seal off the space between mandrel 10 and support member 13. Additional sealing means 54 and 55 are provided for sealing off the space between upper end plate 21 and support member 13.

Similarly, various sealing means are provided for the lower portion of the packer apparatus. Thus, sealing means 60 and 61 are arranged on lower stationary member 34 and are adapted to seal off the spaces between stationary member 34 and mandrel 10, and between stationary member 34 and lower support member 14, respectively. Sealing means 62 are arranged on lower support member 14 and are adapted to seal off the space between lower support member 14 and mandrel 10, and sealing means 63 and 64 are adapted to seal off the space between lower end plate 22 and lower support member 14.

Each of the sealing means may be suitably C-ring seals. The upper ends of filler sleeve 26 and outer sleeve 27 of assembly 20 are bonded to upper end plate 21. Lower end plate 22 has secured thereto a ring 70 provided with a rounded surface adapted to engage the lower end of outer sleeve 27. The filler sleeve 26 is bonded to lower end plate 22.

FIG. 2 clearly shows the relative positions of mandrel 10, bladder 15, filler sleeve 26, reinforcing sleeve 25, and outer sleeve 27.

FIG. 3 shows the inner bladder 15 more clearly including the upper and lower recess portions 16 and 17, respectively, which provide the upper and lower lip elements 18 and 19 therefor.

To assemble the apparatus, the lower stationary member 34 is threaded to mandrel 10. Then lower support member 14 is arranged on mandrel 10. Assembly 29, having been previously fabricated, is threadedly connected to lower support member 14, and inner bladder 15 is inserted. Upper support member 13 then is arranged on mandrel 10 and threadedly connected to upper end plate 21. Upper stationary member 32 then is secured to mandrel 10, and head 36 is secured to upper support member 13. A proper amount of fluid is applied in any desired manner to chambers 40 and 41 and passageway 12.

Another manner of fabricating the packer is as follows. The lower stationary member 34 is secured to mandrel 10, and lower support member 14 is arranged thereon. Then, the lower end plate 22 is connected to lower support member 14, the sleeve 25 having been previously connected to end plates 21 and 22. Filler sleeve 26 and a backup mandrel then may be fitted on mandrel 10, the backup mandrel being a substitute for inner bladder 15. Upper support member 13 then is arranged on mandrel 10, and upper end plate 21 is connected thereto. Outer sleeve 27 then is mandrel wrapped (or molded) on end plates 21 and 22 and sleeve 25, and upper end plate 21 is disconnected from upper support member 13, after which member 13 is removed, and the backup mandrel is replaced by inflatable bladder 15. Then, upper support member 13 is arranged again on mandrel 10 and connected to upper end plate 21, after which upper stationary member 32 is secured to mandrel 10, and head 36 is secured to upper support member 13. Inflate fluid is supplied to chambers 40 and 41 and passageway 12 in any desired manner. Inner bladder 15 is easily inserted or taken out whenever desired, as there is no bond between bladder 15 and filler sleeve 26. In the event bladder 15 is damaged, it may be readily replaced, and in the event outer sleeve 27 is damaged, it may be stripped and replaced. Outer sleeve 27 may be separated from filler sleeve 26 readily as there is little rubber interconnection through sleeve 25. By using galvanized braid wire as the reinforcing sleeve 25, any rubber bond to the braid wire is prevented, and any connection therebetween is only a mechanical one.

Thus, the metallic skeleton, that is, sleeve 25 and end plates 21 and 22, may be recovered whenever desired and may be used until actual wearing out or the reinforcing sleeve breaks.

The layer-built packer has advantages over single piece packers because the former permits the use of a different material for each bladder; the material selected being one that functions best in the particular location it is used. In either the layer-built or single-piece type inflatable packer construction, it is important to prevent extrusion of the packer bladder through the openings formed in the wire reinforcing sleeve or braid upon expansion of the packer in the borehole and upon the resultant application of differential pressure across the packer. In practice, inflation of the packer to 1.5 times its normal diameter results in an elongation of about 300% to the bladder rubber nearest the packer mandrel. The intermediate and exterior portions of the packer are subjected to only about

170% elongation. Thus, in the single-piece packer all of the rubber compound must be formed of a softness to permit 300% elongation of the bladder, which is about 60 Shore durometer. This necessitates compromising on the extrusion resistance of the outer cover portion of the packer. The layer-built construction permits use of a number of elastic compounds to suit borehole conditions. For example, bladder 15 may be formed of 60 durometer natural rubber to give maximum elongation and strength at borehole temperatures. Intermediate sleeve or bladder 26 may be formed of natural or synthetic rubber of 90 durometer hardness to prevent extrusion of the soft bladder through the braid reinforcement; and outer sleeve 27 may be formed of Buna 5 or neoprene of 90 durometer hardness to achieve maximum protection from abrasion and chemical attack in the borehole. Also, under extreme high pressure conditions where the borehole temperature does not exceed 250° F., intermediate sleeve 26 may be formed of polyurethane in order to take advantage of the extreme high strength qualities of this material to prevent extrusion of the bladder through braided sleeve 25. In this instance, bladder 15 and the cover sleeve 27 protect the polyurethane sleeve from acids, alkalines, and hot water, which would destroy it.

These examples of the materials for use are not to be considered to limit the invention to these specific compounds or hardnesses. Instead, they are given as an illustration of the flexibility and adaptability of the layer-built construction of the present invention.

As an example of the sizing of the layer-built packer, the three separate elastic sleeves or bladders for a 7-inch outside diameter packer have the following dimensions: The innermost bladder 15, the intermediate bladder 26, and the outer cover bladder 27 are respectively $\frac{3}{4}$, $\frac{3}{8}$, and $\frac{1}{2}$ inch thick. Other size packers would have proportionately these bladder thicknesses.

In operation, the packer is lowered in the borehole in deflated condition, and fluid is pumped through passageway 11 to the interior of bladder 15. When the packer has been expanded, pressure on the packer, as for example pressure exerted by a hydrostatic column above the packer, moves lower support member 14 downwardly to cause fluid to flow from reservoir 41 to reservoir 40, which moves upper support member 13 upwardly. This tends to distribute the hydrostatic load between the two supporting end plates.

The packer end plate fluidly communicates with recesses 16 and 17 and acts against lips 18 and 19 to seal off the space between bladder 15 and mandrel 10 adjacent the ends of bladder 15.

In the event inner bladder 15 becomes damaged, it is readily replaced by removing head 36, upper stationary member 32, and upper support member 13. With these elements removed, bladder 15 may be replaced and upper support member 13, upper stationary member 32, and head 36, respectively, replaced in that sequence.

If outer sleeve 27 is damaged, head 36, stationary member 32, and support member 13 are first disconnected. Then, assembly 20 is removed by disconnecting lower end plate 22 from lower support member 14. Assembly 20 may be then repaired by stripping off outer sleeve 27 and replacing that sleeve, or if necessary, also stripping off sleeve 26, replacing both filler sleeve 26 and outer sleeve 27 and rebonding both sleeves to sleeve 25 and upper and lower end plates 21 and 22. After repairing assembly 20, it may be then replaced by connecting lower end plate 22 to lower support member 14 and reconnecting upper support member 13, stationary member 32, and head 36. Either or both sleeves 26 and 27 may be replaced while connected to mandrel 10 by the alternative fabricating procedure noted supra. Thus, bladder 15 and assembly 20 may be easily repaired whenever desired and may be used until actual wearing out or until reinforcing sleeve 25 breaks.

Having fully described the elements, nature, objects, and operation of our invention, we claim:

1. A well packer comprising:
a mandrel;
first and second spaced-apart supporting means slidably 5
and replaceably arranged on said mandrel;
first and second end plates releasably threaded to said
first and second supporting means, respectively;
an inflatable inner sleeve surrounding said mandrel be-
tween said first and second supporting means and
formed to provide sealing means adjacent the ends
thereof for sealing off fluid flow between said man-
drel and said sleeve and said supporting means;
an expandible filler sleeve surrounding said inner sleeve
and bonded to said end plates at each end thereof; 15
an expandible outer sleeve surrounding said filler sleeve
and bonded at one end to said first end plate;
a pervious, metallic reinforcing sleeve comprising
braided ribbons or wire arranged between said filler
and outer sleeves and secured to said end plates, the
other ends of said outer sleeve being secured in place
between said reinforcing sleeve and a portion of said
end plate;

10

15

20

said inner sleeve being removable and replaceable upon
removal of either supporting means from said man-
drel; and

passageway means provided in said mandrel for con-
veying fluid for inflating said inner sleeve, said inner
sleeve being made of material having greater elas-
ticity and less durometer hardness than the mate-
rial of which said outer sleeve is made.

2. A well packer as described in claim 1 wherein said
filler sleeve is made of material having substantially the
same durometer hardness as and greater elasticity than
the material of which said outer sleeve is made.
